UNITED STATES PATENT OFFICE.

FRIDOLIN POLZER, OF NEW YORK, N. Y., ASSIGNOR TO THE E. H. HOTCHKISS COMPANY, OF NORWALK, CONNECTICUT, A CORPORATION OF CONNECTICUT.

COMBINATION BINDING MACHINE.

Application filed June 9, 1921. Serial No. 476,250.

My invention relates to combination binding machines capable of being employed for stapling or securing several sheets or layers of paper or other material to each other.

5 One of the objects of the invention is the provision of such a machine which is provided with a staple securing and straightening member or slide, preferably working parallel to the plunger of the machine. This 10 securing and straightening member is provided for the purpose of holding the strip of staples employed with the machine during the operation of cutting off a staple, and for straightening the staple and guiding the 15 same until the staple is driven home and clinched.

A further object of the invention is the provision of a combination binding machine which is operable without regard to 20 the length of the prongs of the staple employed; in other words, the present machine is capable of and designed for use with staples of varying lengths as distinguished from machines as now constructed which are 25 capable of use with staples of one length only.

The advantage of my machine over machines as now constructed is obvious inasmuch, as just pointed out, my machine may be employed with staples of varying lengths whereas with other types of machines a machine must be designed for each length of 30 staple employed.

A further object of the invention is the provision of a machine of the character designated wherein and whereby if desired the staples may be fed through the machine by hand instead of automatically. The advantage of such a machine resides in the fact that in case it should be desired momentarily to change the staples employed to staples having prongs of a different length, it is a simple matter to remove the strip of staples already in the machine and to substitute 35 staples having prongs of a different length which may be fed through the machine by hand for a staple or two or as many staples as may be desired. This strip may then be removed and the original strip substituted.

40 A further object of the invention is the provision of an improved knife upon which the strip of staples may rest as it travels

through the machine, the body portion of the strips as distinguished from the prongs, engaging the upper face of the knife to be 55 supported thereby instead of having the strip resting upon the ends of the prongs of the staples as in the machines as now constructed. This construction, of course, enables staples having prongs of various 60 lengths to be employed in the machine with facility.

A further object of the invention is the provision of what may be termed a combined feed and back-stop which mechanism 65 cooperates with the securing and straightening member already referred to so as to prevent rearward movement of the strip of staples and so as to feed the strips forwardly when desired.

70 A further object of the invention is the provision of a pressure lever which merely rests upon the top of a strip of staples as the same is fed through the machine and which cooperates with a locking device in 75 such a manner as to be capable of being lifted from the staple strip so that the strip may be removed and a new strip substituted and fed through by hand if desired.

The locking device is so arranged that 80 when moved to releasing position it will not only lift the pressure lever but will move the combined back-stop and feeding lever also out of operative position to permit feeding of the staples by hand, or if 85 desired after a new strip has been placed in the machine the locking means may be tripped and the staples fed through automatically.

In the accompanying drawings wherein 90 I have illustrated an embodiment of my invention,—

Fig. 1 shows in sectional elevation a machine embodying my invention with all of the parts in position, ready for the stapling 95 operation;

Fig. 2 is a view similar to Fig. 1, showing the positions of the various parts of the machine when the staple securing and straightening means has been moved downwardly to staple securing position, and the plunger is just about to cut the staple off the strip;

Fig. 3 is a view similar to Fig. 1, show-

ing the positions assumed by the various parts of the machine when the plunger of the machine and the staple straightening and securing means have been moved to their extreme downward position;

Fig. 4 is a plan view of the bottom of the housing of the machine; and

Fig. 5 is a front elevation of the staple securing and straightening means.

Referring now to the drawings in detail, 10 —1 designates the base of my machine which base may be of any desired shape and is provided with pads 2. Mounted upon the base 1 is an anvil 3 which is 15 adapted to be engaged by the ends of the prongs of the staples during the clinching operation. Mounted upon the base 1 and preferably, though not necessarily, pivoted thereto is a housing 4, which in the present 20 instance is shown pivoted to the base 1 at 5.

The housing immediately above the anvil is provided with a guideway 6 for the plunger 7 of the machine and with a guideway 8 for the staple securing and straightening 25 member 9 hereinafter to be referred to in detail. The plunger 7 carries a coil spring 10, the lower end of which is adapted to engage the upper part 11 of the housing, the upper end of this spring being engaged by a cap 12 30 by which the machine is manipulated.

The staple securing and straightening member 9 already referred to comprises a comparatively thin plate provided with legs 13 and 14, which plate is adapted to slide 35 vertically in the guideway 8 in the housing of the machine. The upper part of the staple securing and straightening member 9 is provided with an elongated slot 15 through which a small screw 16 is adapted to 40 pass and which screw is secured to the plunger 7 of the machine. It is to be understood, however, that the slot 15 just referred to is of larger dimensions than the screw 16 so that the staple securing and straightening 45 member may have movement relatively to the plunger 7. The upper part of the staple securing and straightening member 9 is provided with laterally extending lugs 17 and one end of a coil spring 18 which is carried 50 within the plunger spring 10 already referred to is adapted to rest upon this end of the staple securing and straightening means, the other end being engaged by the cap 12 already referred to.

From the description thus far given it will be seen that I have provided a plunger and a staple securing and straightening member in a housing, these two members, that is to say the plunger and the staple securing and straightening member, being so mounted as to be reciprocated vertically in the housing of the machine, the plunger and the staple securing and straightening member having 60 movement parallel to each other and being 65 movable at certain times independently of

each other. This arrangement is provided so that the staple securing and straightening member may move down to staple-securing position before the plunger reaches that point in its travel where the staple is cut off 70 and the forward end of the strip being fed through the machine.

It will be seen also that I have provided springs for each of these members so that they will automatically return to their initial position, that is to say, to the position shown in Fig. 1.

Secured to the housing of the machine in any suitable manner is a member which I shall hereinafter term a knife designated 19. 80 This member is adapted to receive a strip of staples which are fed into the machine from the rear thereof, that is to say from the right-hand end as viewed in Fig. 1 and to be engaged by the body portion of the strip of staples as distinguished from the ends of the prongs of the staples, and to cooperate with the plunger 7 and the staple securing and straightening member 9 so that when the parts are moved to the position shown in 90 Fig. 2 for example or just slightly further, the forward staple of the strip will be cut off by the plunger, the staple cut off being held up to this time in position for the cutting operation by the staple securing and straightening member and as will herein-after be pointed out, being then straightened and, so to speak, guided during the 95 driving and clinching of the staple.

The plunger 7 is provided with a lug 20 which is adapted to be straddled by the legs 13 and 14 of the staple securing and straightening member, this lug cooperating with a lever 21, forming part of what I shall hereinafter term a combined feeding means and back-stop. This lever 21 is provided with a pair of lugs 22 and 23 between which the lug 20 is adapted to be reciprocated and which lugs are at times engaged by the lug 20 so as to rock the lever 21 about its pivot. Secured to one arm of the lever 21 is another lever 24, the levers 21 and 24 together constituting a combined feeding means and back-stop for the staple. The lever 24 at its rear end is provided with a spring 25 passing about a pin 26, the other end of the spring 110 cooperating with the pressure lever 27 to be hereinafter referred to more in detail.

The front end of the lever 24 is adapted 115 to engage the strip of staples at a point between adjacent prongs thereof and when the strip is in position for the cutting operation the front end 28 of the lever 24 will be in engagement with the strip of staples between the third and fourth staples of the strip. With the front end 28 of the lever 24 in this 120 position rearward movement of the strip of staples is prevented.

The pressure lever 27 already referred to 130 is pivoted in the housing of the machine at

29 and cooperates with the spring 25 already referred to, to merely hold the strip of staples down against the top of the knife 19. By reason of the provision of the combined feeding means and back-stop already described, the pressure plate 27 is free of teeth.

The locking member or lever 30 is pivoted at 31 to the housing of the machine and is adapted to engage the rear end of the pressure lever 27 and in the position shown in Fig. 1 the parts are in position for automatic operation of the machine. If it be desired, however, to remove a strip of staples from the machine for any reason whatsoever, or to substitute a new strip of staples or to operate the machine by hand as distinguished from automatic operation of the machine, it is merely necessary to swing the locking lever 30 to its extreme left-hand position, which movement of this lever will lift the pressure plate 27 and also the lever 24 so as to permit of an unobstructed movement of the strip of staples for any reason whatsoever.

In operation the locking lever 30 is preferably moved to its extreme left-hand position to raise the pressure lever 27 and the lever 24 upwardly and a strip of staples 32 is then fed into the machine with the prongs straddling the knife 19 and the body portion of the strip resting upon the upper surface of the knife, the strip being moved into the machine until the front end thereof engages the side 33 of the guide 6 for the plunger 7. The locking lever 30 is then moved to the position shown in Fig. 1.

It is to be understood, however, that if desired the lever 30 may be left in the position shown in Fig. 1 in loading the machine as the strip of staples may be stiff enough to permit of the strip being forced beneath the pressure plate 27 to the position above described. Several sheets of paper or other material which it is desired to staple may then be inserted upon the anvil 3, the frame 4 of the machine being rocked slightly about the pivot 5 for this purpose. The cap 12 is then moved downwardly to carry the plunger 7 and the staple securing and straightening member downwardly also. The staple securing and straightening member 9 at the beginning of this movement is slightly in advance of the plunger 7 so that the legs of the member 9 will enter between prongs of the first and second staple of the strip before the plunger 7 will have been moved downwardly sufficiently far to cut off the forward staple. By this I am enabled to securely hold my staple in position for the cutting operation. As the plunger 7 and the member 9 continue their downward movement the plunger will cut the forward staple from the strip and as soon as this forward staple is cut off it will be forced by

the plunger downwardly, being guided, however, in its movement not only by the guideway 6 but also by the face of the staple securing and straightening member 9 and this member 9 is active until the staple has been forced through the papers or other material being stapled, and clinched.

It will be seen, therefore, that in cutting the staple from the strip member 9 effectively prevents any forcing of the staple out of its proper position or any bending of the prongs of the staple and hence I am assured that the staple will be maintained in proper position and the prongs thereof maintained in proper position so that the staple will always be driven home and clinched. This arrangement also prevents clogging of the machine for it will be obvious that should a staple be bent in being cut off and driven through the paper, that the machine will be clogged and that the papers or other material will be improperly stapled. Should the machine become clogged it would necessitate the removal of the strip of staples and waste of the entire strip.

Still referring to the operation of my machine,—it will be seen that as the plunger 7 moves downwardly due to pressure upon the plate 12, the lug 20 carried by the plunger will be carried downwardly also and finally it will engage the lower lug 23 on the lever 21 forming part of the combined feeding means and back-stop above referred to. This engagement of the two lugs will cause the lever 21 to be rocked about its pivot to carry the lever 24 to the right as viewed in Fig. 1 and this movement of the lever 24 takes place before the first staple of the strip is cut off. The lever 24 is moved to the right or rearwardly until the front end 28 of the lever engages a strip of staples between the third and fourth staples of the strip and will remain in this position throughout the remainder of the downward movement of the plunger 7 and the staple securing and straightening member 9. It will be seen, therefore, that not only is the strip of staples securely held during the cutting operation and that not only is the staple cut off properly straightened and guided, but after the forward staple is cut off rearward movement of the strip of staples is also prevented. After the plunger 7 and the staple securing and straightening member 9 have reached the limit of their movement downwardly, that is to say, after the staple has been driven home and clinched, the hand of the operator may be removed from the cap 12 and the springs 10 and 18 will return the parts to the position shown in Fig. 1. On this movement of the plunger 7 and the staple securing and straightening means 9, the lug 20 carried by the plunger will engage the lug 22 of the lever 21 to rock the lever in

the opposite direction to which it was rocked on downward movement of the plunger. This movement of the lever 21 will carry the lever 24 forwardly, that is to the left, as viewed in Fig. 1 and inasmuch as the front end 28 of this lever is in engagement with the strip of staples between the third and fourth staples thereof, the strip will be fed forwardly until the forward staple of the strip will engage the wall of the guide 33 for the plunger. The parts are now in position for another stapling operation.

From the foregoing it will be seen that I have provided a combination binding machine wherein means have been provided having movement parallel with the plunger of the machine for securing and straightening staples during the stapling operation so that clogging of the machine is prevented and so that a proper driving and clinching of the staples is assured.

It will be seen also that I have provided a combined back-stop and feeding means for the strip of staples whereby the strip of staples will always be fed forward properly and whereby rearward movement of the strip is effectually prevented.

It will be seen also that I have provided an improved pressure plate which is adapted to maintain the body portion of the strip of staples in engagement with the knife and which pressure plate by reason of my improved feeding means and back-stop is free of teeth.

It will be seen furthermore that if desired I may raise the pressure plate and combined feeding means and back-stop out of their normal position so as to operate the machine by hand if desired, this being desirable at times when it may be necessary or desirable to employ longer or shorter pronged staples than the machine happens to be loaded with.

It will be seen also that my machine is capable of operating with staples, the prongs of which may be of varying lengths, thereby avoiding the necessity of manufacturing or furnishing a machine for each specific length of prong that may be used.

While I have described a specific embodiment of my invention it is to be understood that changes may be made in the details thereof without departing from the spirit and scope of my invention.

What I claim is:

1. A combination binder comprising a plunger, an anvil cooperating therewith, a support for a strip of staples, a pressure member adapted to engage a strip of staples as the same is in place upon its support, and a locking member for locking said pressure member out of operative position.

2. A combination binder comprising a plunger, an anvil cooperating therewith, a

support for a strip of staples, a pressure member for engaging the strip of staples as the same rests upon its support, means for feeding the strip through the machine, and a locking lever for locking said pressure member and staple feeding means out of operative position.

3. A combination binder comprising a housing, guideways in said housing, a plunger in one of said guideways, a staple securing and straightening member in the other of said guideways, a cap secured to said plunger, a spring interposed between the top of said housing and said cap, and a spring surrounded by the spring first mentioned, one end of the last-mentioned spring engaging said cap and the other the top of said staple securing and straightening member.

4. A combination binder comprising a housing, a plunger, a staple securing and straightening slide, provided with an elongated slot, said plunger and slide having vertical movement in said housing parallel with each other, a pin passing through said slot and secured to said plunger, said plunger and slide being adapted for manual movement in one direction, and springs for automatically moving said plunger and slide in the other direction.

5. A combination binder comprising a knife for supporting a strip of staples, a plunger cooperating with said knife for cutting staples from said strip and driving the same, a pressure member for engaging the strip of staples as the same is supported by said knife, and a lever provided with a double-throw cam, said lever when moved in one direction raising the pressure member out of operative position and when moved in the opposite direction locking the pressure member in inoperative position.

6. A combination binder comprising a knife adapted to receive and support a strip of staples, a plunger cooperating with said knife and adapted to cut a staple from said strip of staples and drive the same, a feeding means for feeding the strip of staples along said knife as the plunger is reciprocated, and means for moving said feeding means out of feeding position and locking the same in inoperative position.

7. A stapling machine comprising a plunger, staple straightening means adjacent said plunger, and a spring surrounding the plunger for setting said straightening means to straightening position.

8. A staple binder having a supporting bar for supporting a staple strip that is composed of individual staples connected in series, said bar having a cutter edge at one end, means for feeding said strip along the said bar so that said strip will project beyond said cutting edge, means to limit such projection of the strip to correspond to a

single staple and operative also to serve as a guide for one edge portion of said single staple, a plunger having a cutter edge to co-operate with the cutting edge of the bar and operative to sever said single staple and drive the same, auxiliary guide means for guiding the opposite edge portion of the

said single staple, and means operated by a spring surrounding the plunger for setting said auxiliary guide means to the guiding position.

This specification signed this 31st day of May, 1921.

FRIDOLIN POLZER.
